Attorneys.

UNITED STATES PATENT OFFICE.

WILLIAM E. ROSS, OF CLEVELAND, OHIO, ASSIGNOR TO THE ROSS MANUFACTURING COMPANY, OF CLEVELAND, OHIO, A CORPORATION OF OHIO.

WHEEL-DRESSER.

1,256,167.

Specification of Letters Patent. Patented Feb. 12, 1918.

Application filed January 27, 1917. Serial No. 144,986.

To all whom it may concern:

Be it known that I, WILLIAM E. Ross, a citizen of the United States, resident of Cleveland, county of Cuyahoga, and State 5 of Ohio, have invented new and useful Improvements in Wheel-Dressers, of which the following is a specification, the principle of the invention being herein explained and the best mode in which I have contemplated

10 applying that principle, so as to distinguish it from other inventions.

My invention relates to devices for dressing wheels and particularly to that class of such devices used for dressing carborundum 15 or other composition wheels. Said improvements are designed to have an effect upon the wheel that is dressed wholly different from that effected by any other device of this character with which I am acquainted. Furthermore, my improved wheel dresser is 20 designed to greatly increase the amount of work which can be attained with a wheel of a given character.

The annexed drawing and the following 25 description set forth in detail certain means embodying my invention, the disclosed means, however, constituting but one of various mechanical forms in which the principle of the invention may be applied.

30 In said annexed drawing:

Figure 1 represents a side elevation of my improved wheel dresser mounted in a toolholder in a new and improved manner hereinafter fully described; Fig. 2 represents 35 upon an enlarged scale a broken plan view of my improved wheel dresser; Fig. 3 represents a central longitudinal section taken in the plane indicated by the line III—III, Fig. 1, and Fig. 4 represents a central section taken in the plane of the axial line of the wheel dresser, as shown by line IV—IV, Fig. 3.

The illustrated embodiment of my invention comprises an integral rotatable member

5 1 in which grooves 2 are formed either by milling, grinding, die casting, die sinking or in any other approved manner. These grooves in the form shown are of equal width throughout, and comprise two series

0 crossing each other and intersecting the two planes of the sides of the member 1, the members of each series being equidistant from each other, as shown in Fig. 2. In the form shown, these grooves run parallel with

planes intersecting the axis of rotation at an 55 angle of 45°. As a result of the above-described construction, a plurality of relatively fixed diamond shaped areas 3 are formed, each of which is entirely disconnected from the others, is equal in size to every other and 60 lies in the surface of a cylinder whose axis coincides with the axis of rotation of the member 1.

Each of these areas furthermore includes two sets of cutting edges 3' 3' and 3'' 3''. 65 These edges are all of equal length as shown and each of the two edges of a given set is angularly disposed with reference to the other, also as clearly shown, and lies in a plane intersecting the axis of member 1. A 70 number of disconnected areas are thus formed, the outermost boundaries of which are lines lying in the surface of a cylinder. These areas as shown, are disconnected across the face of the cylinder; that is, they 75 constitute a number of separate areas systematically arranged and detached both lengthwise and crosswise of the cylinder.

I have found that by altering the size of the areas 3, I obtain different results from 80 the wheels to which the dresser is applied. When it is desired that the wheel to be dressed shall rough finish the work, I decrease the size of the areas and hence the length of the cutting edges. This may be 85 done by increasing the number of intersecting grooves 2 or by increasing the width of the respective grooves. When the sum of all of these areas is equal to from twenty (20) to forty (40) per cent. of the possible 90 cylindrical area of the member, the tool is suitable for preparing a carborundum or emery wheel for rough finishing. When this sum is increased to form forty (40) to eighty-five (85) per cent. of the possible 95 cylindrical area, the wheel to which the tool is applied will be suitable for fine finishing the work.

It is desirable and conducive to efficiency to have the parts of the outer surface of the tool remaining, distributed with substantial uniformity throughout the periphery of the wheel, yet it is not essential that this uniformity be more than reasonably approximate in degree; and I wish to be understood 105 as meaning, when I use the word uniformity, merely a reasonable approximation to absolute uniformity or such uniformity as will

provide the same or similar result to that produced by the device shown. It is obvious also that while the limits of proportions which I have specified above are the useful limits in connection with carborundum wheels of usual composition, these proportions of dimensions may be varied to some extent, when my dressing wheels are constructed to dress wheels of novel, or less well known composition, and I desire accordingly to be understood as not restricting myself to the percentages specified above, save in the present connection.

It will be noted from the above-described construction that every plane passing through member 1 at right angles to its axis intersects some of the areas 3. This results, from the fact that these areas overlap each other and so no part of the grinding wheel to which the dresser is applied escapes the action of the cutting edges, regardless of the speed at which the dresser is caused to travel across the periphery of the grinding wheel. Uniformity of operation on the latter is thus obtained.

By providing each area with two cutting edges placed angularly with reference to each other, wedges are formed the apices of which perform the initial part of the operation and such arrangement seems to produce the most advantageous results, although the prime essential appears to consist in the provision of a straight cutting edge located in the surface of a cylinder and an adjacent superficial area also in such surface, together with the staggered relationship of the cutting edges whereby they overlap each other laterally and produce the above-mentioned uniformity of operation.

I have also found it preferable, though not absolutely indispensable, to make both sets of grooves of equal width, as shown.

I have furthermore found that wheels dressed with the above described tool will perform a grinding operation for a greatly increased length of time before it is necessary to again re-dress them, as compared with grinding wheels dressed by means of other devices heretofore known and of which I am aware.

The above described member may be mounted in any suitable holder or handle but I have illustrated one form of holder which I have found to be suitable and which I shall now describe.

The member 1 is provided with an axial bore in which is tightly wedged a bushing 4. This bushing is formed with two end conical bearing surfaces 5, Fig. 3, which terminate at their inner ends at a cylindrical pocket 6, as shown in Fig. 4. The handle or holder is provided with the shank 7 formed with a yoke whose two arms 8 are provided with screws 9 whose inner ends 10 are provided with conical journal portions

11 corresponding with and adapted to fit the conical bearing surfaces 5. These screws are adjustable and are held in position by means of lock nuts 12.

What I claim is:—

1. In a wheel dresser, a rotatable member of unitary structure, provided with a multiplicity of relatively disconnected areas formed by continuous oblique grooves whose outermost boundaries are lines lying in the surface of a cylinder; said areas extending lengthwise and crosswise of the cylinder and being so located that every plane passing through said member and perpendicular to the axis will intersect some of such areas. 70

2. In a wheel dresser, a rotatable member of unitary structure, the surface of which is interrupted by grooves running parallel with planes intersecting the member's axis at angles other than one of ninety degrees 85 (90°), said grooves being of a form and spaced from each other distances such that disconnected areas are formed extending lengthwise and crosswise of the cylinder and having cutting edges for boundary lines, 90 said areas lying in a cylindrical surface whose axis coincides with the axis of rotation of said member.

3. In a wheel dresser, a rotatable member formed with a multiplicity of disconnected areas bounded by cutting edges and lying in the surface of a cylinder having its axis coinciding with the axis of rotation of said member, said areas extending lengthwise and crosswise of the cylinder and being formed by grooves parallel with planes intersecting said axis at an angle other than one of ninety degrees (90°). 95

4. In a wheel dresser, a rotatable member provided with a plurality of peripheral relatively disconnected areas bounded wholly by lines in the shape of helices and lying in the surface of a cylinder having its axis coinciding with the axis of rotation of said member and so located that every plane passing through the member and perpendicular to said axis will intersect such areas, each of the latter including a helix-shaped cutting edge, all of said areas being fixed relatively to each other, said areas detached both lengthwise and crosswise of the cylinder. 100

5. In a wheel dresser, a rotatable member provided with a plurality of peripheral relatively disconnected and fixed areas lying in the surface of a cylinder having its axis coinciding with the axis of rotation of said member, and so located that every plane passing through the member and perpendicular to said axis will intersect such areas, each of the latter including two straight cutting edges forming an angle with each other. 105

6. In a wheel dresser, a rotatable member provided with a plurality of peripheral rela-
